TOOL-HOLDER ASSEMBLY

Stanford P. Bruce, Detroit, Mich., assignor to
 Wheel Trueing Tool Company, Detroit, Mich.,
 a corporation of Michigan

Application October 26, 1948, Serial No. 56,499

1 Claim. (Cl. 125—11)

1

The present invention relates to a new and improved type of tool holder assembly.

More particularly, the invention relates to a tool holder adapted for use with diamond dressing tools in mechanisms for dressing or trueing the surface of an abrasive wheel.

It is common practice to dress the surface of an abrasive wheel periodically by use of a diamond tool which is caused to traverse the surface of the abrasive wheel as the wheel rotates about its axis to dress or true the surface. Continued use of the diamond dressing tool tends to wear the surface of the diamond point unevenly with the result that the edge of the diamond is dulled and does not present a good cutting surface to the abrasive wheel. To overcome this difficulty, it has been suggested that the diamond point be secured in a rotatable mounting so that the diamond point may be periodically rotated, thus presenting a new sharp edge to the work. This innovation presents a problem in that the working clearances that are necessary in the design of a rotatable tool holder give rise to an objectionable vibration of the tool during its operation, commonly known as "chattering." This chattering effect tends to make the operation of the tool unsteady with the result that the dressing is not as accurate as it should be.

An object of the present invention is to provide a tool holder particularly adapted for use in diamond dressing tools which is capable of intermittent rotation, but in which the effects of chattering are substantially or completely eliminated.

Other and further objects of the invention will be apparent from the description of the attached sheets of drawings.

On the drawings:

Figure 1 is a view of the grinding wheel dressing mechanism assembled and in position for the dressing of an abrasive grinding wheel.

Figure 2 is a front end view of the assembly as shown in Figure 1.

Figure 3 is a cross-sectional view taken along the line III—III of Figure 2.

Figure 4 is an end view of the assembly with the indexing collar of the assembly removed.

Figure 5 is a cross-sectional view taken along the line V—V of Figure 4, with parts in elevation.

Figure 6 is an exploded view of the assembly showing its component parts.

As shown on the drawings:

In Figure 1, reference numeral 10 denotes in general a guard positioned concentrically with a rotary abrasive wheel 11. A slide 12 is positioned

2

within the guard 10 and holds the dressing mechanism in such a position that a proper drag angle is presented between the axis of the diamond tool and a true radius of the abrasive wheel passing through the point of the tool.

The shank portion 13a of body member 13 of the assembly is held in bore 12a of the slide 12 and is provided with a longitudinally extending notch 13b. A locking screw 14 is threaded into the slide 12 and into the notch 13b to hold the body member 13 rigidly against rotation. A locking collar 15 abuts against the body member 13 and serves to secure a tool adapter 17 within the assembly. A knurled indexing collar 16 is mounted against the locking collar 15 and is secured to the tool adapter 17 which carries a diamond tool 18 provided with a diamond point 19. The diamond tool holder 18 is secured within the tool adapter 17 by means of locking screw 20.

The collar 16 is provided with inscribed numerals 16a to guide the operator in the proper indexing of the tool during rotation. The collar 16 is also provided with a recessed portion 16b terminating in a threaded portion 16c adapted to receive a set screw 21 to rigidly hold the tool adapter 17 such that the tool holder 18 is rotated upon rotation of indexing collar 16.

As best shown in Figure 3, body member 13 is provided with a radially extending flange portion 13d formed into a shoulder portion 13e having an internally threaded boss 13f for receiving locking screws 22 for securing the restraining collar 15 against the shoulder 13e and the flange 13d. The body member 13 is also provided with an internal bore 13g which extends into the shank 13a of the body member 13. The bore 13g in the body member 13 is adapted to rotatably mount the pilot 17a of a tool adapter 17. A bearing surface 13h is formed in the body member 13 for seating a radially flanged portion 17b of the tool adapter 17. As shown in Figure 3, the diameter of the radially extending flange portion 17b is somewhat less than that of the bearing surface 13h. The flange portion 17b is provided with peripheral notches 17c for receiving ball detent means as will be hereinafter described. Disposed between the flange portion 17b of the tool adapter 17 and the surface of the restraining collar 15 are an oilite bearing 23 and a resilient spring washer 24. The resilient spring washer 24 is held under compression by the restraining collar 15 to effect a thrust-bearing relationship between the flange portion 17b and the bearing surface 13h. This arrangement acts

to prevent any chattering of the tool which would be occasioned by the working clearances necessary in the assembly. As shown by the dotted lines in Figure 3, the tool adapter 17 is provided with an internal bore 17d for receiving a conventional diamond point holder 18, which is locked in the tool adapter 17 by means of a locking screw 20 being inserted through an aperture 17e in the tool adapter 17.

As best shown in Figure 5, a ball detent means is provided in the assembly to control the rotation of the tool adapter so that a uniform indexing of the tool may be accomplished. The shoulder 13e of body member 13 is provided with a bore 13i extending therethrough for receiving a spring 25 and ball 26. The spring 25 is compressed by locking collar 15 and urges the ball 26 into an appropriate notch 17c of the flanged portion 17b.

In normal operation, the tool will be indexed after each complete cycle of dress, consisting of two passes across the grinding wheel face. At such time, the operator merely turns the knurled indexing collar 16 to the next appropriate number, causing the balls 26 to drop in the next series of notches 17c, in which position a new dressing edge is presented by the diamond point to the abrasive wheel to be dressed and maintained until the next dressing cycle has been completed. As a result, after a series of such indexing operations, the diamond point assumes a generally pyramidal shape most suitable for dressing abrasive wheels, and may be used for an indefinite period of time. In assembling the tool holder assembly of the present invention, the tool adapter 17 is inserted into the body member 13 by means of the pilot 17a being inserted into the bore 13g of the body member 13, causing the flange 17b to seat against the bearing surface 13h of the body member 13. The oilite bearing 23 is then inserted over the shoulder 17f of the tool adapter 17 and against the opposite face of the flange portion 17b. Next, resilient spring washer 24 is also inserted over shoulder 17f. It is to be noted that the positions of the bearing 23 and the spring washer 24 may be reversed without impairing the operation of the device. Next, the restraining collar 15 is inserted over the shoulder 17f and against the shoulder 13e of the body member 13 and is secured to the body member 13 by means of the locking screws 22 passed through bores 15a in the restraining collar 15, and threaded into the boss portions 13f on the body member 13. Thus, the containing collar 15 causes the spring washer 24 to be compressed and to urge the flange 17c against the bearing surface 13h at all times. Finally, the knurled indexing collar 16 is slipped over the shoulder 17g and rigidly secured thereto by the insertion of a lock screw 21 threaded

5 into internally threaded portion 16c in collar 16 and against collar 17g. A conventional diamond holder 18 with a diamond point 19 may be inserted into the tool adapter 17 and secured therein by means of a lock nut 20 inserted through an aperture 17e in the tool adapter 17.

10 It will be seen from the above description that the present invention provides a tool holder especially adapted for use in connection with diamond dressing tools and provides for intermittent manual rotation of the diamond tool thus maintaining the diamond tool in a sharp condition at all times, while eliminating the undesirable chattering or vibration of the tool during the dressing operation.

15 It will, of course, be understood that various details of construction may be varied through a wide range without departing from the principles of this invention and it is not the purpose to limit the patent granted hereon otherwise than necessitated by the scope of the appended claim.

I claim as my invention:

20 In a supporting assembly for a pointed tool for use in the dressing of rotary work such as grinding wheels and the like, a holder having an axial pilot bore, an adapter having at one end a pilot rotatably journaled in said bore and having at its other and free end means for receiving and lockingly holding a pointed tool in substantially 25 axial alignment with said bore, said adapter including a radially extending flange between its said end and at substantially right angles to said pilot, radially disposed peripheral notches on said flange, rotary index control mechanism between the periphery of said flange and said holder comprising a radially urged resilient element carried by said holder for cooperation with the radial notches of said flange, resilient thrust resisting means in cooperation with a radial face of said flange between said flange and said tool receiving end of the adapter, and clamping means disposed on the tool receiving end of said adapter holding said resilient thrust means in 30 effective cooperation with the radial flange on said adapter.
